UNITED STATES PATENT OFFICE

111,489

DESIGN FOR A HANDLE FOR KITCHEN UTENSILS AND THE LIKE

Charles Fischer, Newark, N. J.

Application January 11, 1938, Serial No. 74,201

Term of patent 7 years

To all whom it may concern:

Be it known that I, Charles Fischer, a citizen of the United States, residing at Newark, county of Essex, and State of New Jersey, have invented a new, original, and ornamental Design for a Handle for Kitchen Utensils and the like, of which the following is a specification, reference being had to the accompanying drawing, forming part thereof.

In said drawing, Fig. 1 is a side elevation, and Fig. 2 is a top end elevation of a handle for kitchen utensils and the like, showing my new design.

The characteristic features of my design reside in a handle of the conformation shown, having at its lower end a downwardly tapered butt, an

upwardly tapered body portion having curved plane surfaces, an annular bead of enlarged diameter intermediate said butt and said body, and said body having formed in its surface four flutes, spaced ninety degrees apart, said flutes having their bases abutting said bead and extending upwardly from the latter to terminate short of the free upper extremity of the body; said flutes being of tapered width, with converging side margins terminating at the upper end in the plane of the handle body surface.

I claim:

The ornamental design for a handle for kitchen utensils and the like, as shown and described.

CHARLES FISCHER.
